CLAIM

The ornamental design for a post insert for fences as shown and described.

DESCRIPTION

Figure 1.1 is a perspective view of a post insert for fences;

Figure 1.2 is a perspective view thereof;

Figure 1.3 is a back view thereof;

Figure 1.4 is a front view thereof;

Figure 1.5 is a right view thereof;

Figure 1.6 is a left view thereof;

Figure 1.7 is a bottom view thereof; and

Figure 1.8 is a perspective view thereof.

The broken lines shown in figures 1.1 to 1.8 illustrate environment and form no part of the claimed design. The post insert for fences is shown with symbolic break lines to depict variable length of the insert portion and variable diameter of the top cover plate.

1 Claim, 8 Drawing Sheets
